UNITED STATES PATENT OFFICE.

HYMAN STARR, OF NEW YORK, N. Y.

DESIGN FOR A SWEATER.

SPECIFICATION forming part of Design No. 33,989, dated January 29, 1901.

Application filed January 5, 1901. Serial No. 42,251. Term of patent 7 years.

To all whom it may concern:

Be it known that I, HYMAN STARR, a citizen of the United States, residing at New York, borough of Manhattan, and State of New York, have invented and produced a new and original Design for Sweaters, of which the following is a specification, reference being had to the accompanying drawing, forming part thereof, the same showing a front elevation of the new design.

The leading or material feature of the design for a sweater is a neckband arranged open in V shape at the front and having longitudinal ribs which are continued by similar ribs in the body of the sweater.

A indicates the body of the sweater, having ribs *a*.

B indicates the neckband, with a V-shaped front opening *b* and having ribs *b'*, which are formed as continuations of the ribs *a*, so as to produce a uniform effect and design.

What I claim is—

The design for a sweater, as shown and described.

In testimony that I claim the foregoing as my invention I have signed my name in presence of two subscribing witnesses.

HYMAN STARR.

Witnesses:

PAUL GOEPEL,
GEORGE F. GEIBEL.
